METHOD AND APPARATUS FOR WORKING
SHEET MATERIAL

Fred B. Pfeiffer, Akron, Ohio

Application January 30, 1945, Serial No. 575,297

13 Claims. (Cl. 18—19)

1

This invention relates to methods of covering and/or wrapping objects with sheet materials and to apparatus for practicing such methods. It has as its principal object the providing of methods and apparatus for drawing-in-the edge portions of a blank or sheet of material used in stretch-wrapping under more positive control than that disclosed in my co-pending application Serial No. 193,214, filed February 28, 1938. By reference to my said co-pending application page 11, lines thirteen to twenty-four inclusive, and to Figs. 2, 7, 8 and 9 of the drawings accompanying said application it will be seen that edge portions of a blank of sheet material are clamped between two non-collapsible clamps during the beginning of the stretch-wrapping operation and that during the operation of stretching the sheet material about an object being wrapped that the non-collapsible clamps release the edge portions of said blank of sheet material and that said edge portions are caught on or by inwardly moving members or crimpers whereby the said edge portions are drawn inwardly to complete the packaging of an article being wrapped.

I have found that a soft clinging sheet of wrapping material will slip little, if any, on said crimpers and that a hard, stiff material will slip some degree and accordingly ununiform results are obtained from wrapping materials of different characteristics. The present invention overcomes such variations by positively holding said edge portions as they are carried inwardly. The novel method may be practiced in several ways all of which employ the principle of stretch-wrapping wherein the means holding the edges or portions of the edges of a sheet or blank of wrapping material being used are moved or drawn inwardly thereby utilizing substantially the entire area of said sheet or blank in covering the article being wrapped or covered. Although the preferred form of the invention illustrated in this application is shown in connection with stretch-wrapping it will be obvious to those familiar with the art that the methods and apparatus are novel and useful for other purposes and it is my intention that the invention be limited only by the claims.

The foregoing and other objects, features and advantages of the invention will readily appear from the following description in connection with the accompanying drawings, wherein the invention is shown merely by way of illustration and wherein,

Fig. 1 is a top plan view of another form of a

2

machine for practicing the novel method and shown in open position;

Fig. 2 is a side elevation of the machine shown in Fig. 1 shown in closed position in the process of wrapping a bottle;

Fig. 3 is a cross-sectional view taken on line 3—3 of Fig. 2;

Fig. 4 is an enlarged fragmentary detailed view showing the vacuum connecting means for the holding members;

Fig. 5 is a cross-sectional view taken on line 5—5 of Fig. 4;

Fig. 6 is a cross-sectional view taken on line 6—6 of Fig. 5; showing the vacuum line connection to the holding member;

Fig. 6a is a perspective view of a wrapped bottle as it appears after removal from the apparatus shown in Fig. 2, shown on a smaller scale;

Referring to Figs. 1, 2 and 3 it will be seen that 20 a supporting frame 100 rests on a base 101 on which a motor 102 and a gear reduction drive 103 are supported. Frictionally attached to the drive 103 by a frictional clutch 105 is a crank shaft 106. The clutch 105 is provided with an engagement means 107. Rotatably attached to the crank shaft 106 are arms 108 and said arms are pivotally attached to adjustable toggle arms 109 and 110 which pivot on movable pivot pins 111 and fixed pivot pins 112 rigidly attached to the frame 100. 30 Arms 109 are adjustable by means of a turn buckle 113 and are pivotally attached to sheet material channeled holding members support frames 114 by pivot pins 115 which are rigidly attached to the said member 114. The members 114 are supported by means of hinge pins 116 which are rigidly attached to the frame 100. Removably attached by means of screws 118 to frames 114 are sheet material holding members 117. Said channeled holding members 117 are provided 40 with inserts 119 best shown in Figs. 5 and 6. Each member 119 is preferably made of rubber and is formed with a continuous vacuum duct 120 which communicates through narrow slots 121 with a recessed top portion 122. The bottom of said 45 recessed portion is formed with a knurled or channeled surface 123 whereby air may be withdrawn from between a sheet of material 124 and said surface 123 thus making substantially the entire area of said surface available for atmospheric pressure to retain said sheet material in contact with said member 119 during the period the vacuum is maintained. Members 120 are 50 connected by means of a flexible hose connection 130. The opening through said hose connection 130 communicates with the duct 120 through a nipple

55

131 and said nipple has a head portion 132 adapted to retain said nipple in holes 133 formed through the bottom of said members 117 and is held in airtight relation to members 117 by means of washer 134 and lock nut 135. The flexible member 130 is retained in airtight relation with member 131 by means of hose clamps 136. A vacuum line 137 is attached to member 130 by any satisfactory means not shown. Attached to frame 100 by means of a support member 141 is a stop and positioning device 140. Member 140 is attached to the member 141 by screws or any other means found satisfactory. The member 141 is attached to the frame 100 by means of bolts 142. It is to be understood that the invention contemplates adjustment of the device 140 in various positions to accommodate different sizes of objects being operated upon and for this purpose slots may be provided in member 100 as well understood by those familiar with the art. A small air exit channel 145 is provided in the edge portion of the member 117 whereby air trapped between the object being wrapped and the wrapping material is allowed to escape as will hereinafter be explained.

The operation of this form of the invention will now be briefly described in connection with the wrapping of a bottle 85a, however, it is to be understood that by modification of the shape of the holding members 117 and its inserts 119 that various objects of different sizes and shapes may be wrapped. The operation of wrapping is begun with the device in the open position shown in Fig. 1 by the operator manually laying a blank of heat-softenable and heat-sealable wrapping material 124 of suitable size on the holding members 117 and then connecting the vacuum line 137 by means of a valve not shown. This causes the wrapping material 124 to be held firmly at its edge portions, said edge portions being drawn by differential fluid pressure into the recessed portion 122 of the insert 119 where said wrapping material is pressed against the knurled surface 123 as best shown in Figs. 5 and 6. Next the blank of material 124 is heated by a blast of hot air from a blower, not shown, or by heat from any source of supply. When the wrapping material 124 becomes soft enough for the stretch-wrapping operation the operator manually presses the bottle 85a with the bottom of said bottle first in contact with the said wrapping material directly over the stop and positioning device 140. The operator then thrusts the bottle downwardly until the bottom of the bottle rests in position in the device 140 as shown in Fig. 2 with the material 124 stretched about the bottom of the bottle. Since many thermoplastic materials are thermo-elastic, by which is meant that they will return to their unstretched condition when heated it is necessary when the sheet 124 is such a thermoplastic material for the operator to hold the bottle 85a in position in the member 140. Of course automatic gripping means may be provided on the member 140 if found desirable. In the present specific illustration the operator holds the bottle in position by grasping it on its bottom portion under the frame 117 so that the operator's hands and arms are out of the way of the closing jaws of the said frame. The automatic features of the device are next set in motion by the operator closing a switch, not shown, which conducts electrical current to the motor 102. The motor through the gear drive 103 and members 104 and 105 and 107, actuates the crank shaft 106 which starts from the position shown in dotted lines in

Fig. 3. As the crank arm approaches its upward position the arms 108, 109, and 110 move to carry the leaves or jaws of the frame 117 in a hinging motion about the hinge pin 116 until the said crank arm reaches its upwardmost position when the edges of the inserts 119, on which the edge portions of the wrapping material 124 are firmly held, are pressed firmly together catching said wrapping material 124 between them causing the wrapping material to fuse or heat seal on a relatively narrow line following the contour of the closed members 119. The operator may set the automatic mechanism in motion during the time the operator is pressing the bottle downward against the wrapping material 124 in which case the operator will synchronize his motions with that of the device by first pressing the bottle downward and then reaching under the frame 117 and pulling the bottle downward against the member 140 as the members 117 fold together. It is to be understood, as can be seen by reference to Fig. 3, that the inserts 119 protrude a short distance above the edges of the channel in the frame 117. In this operation the positioning device 140 has been adjusted to a height on the frame 100 that the holding device 117 will pass over the top of the bottle 85a held in position on said device. The contour of the frame 117 has also been designed to conform to the shape of the top of the bottle 85a with sufficient clearance to avoid excessive stretch of the wrapping material as said wrapping material is stretched over the said bottle as the surfaces of the holding members 119 move into contact with each other as just described. By reference to Fig. 2 it will be seen that the wrapping material is stretched like a tent from the hinge pin portion of its holding means to the bottom of the bottle and that from the hinge pin portion of the frame 119 upward the wrapping material is fused together a distance away from the bottle with the result that a substantial volume of air is enclosed between the wrapping material and the bottle. Many thermoplastic wrapping materials such as materials now commercially available under the trade names of "Pliofilm" "Koroseal" and "Kodapak" will shrink back when heated and stretched and the stretched material remains heated. Since in the present operation there may be residual heat left in the wrapping material which would cause it to shrink back against the bottle, or if not sufficient residual heat remains in the wrapping material after the wrapping operation it may be desirable to again heat the wrapping material to cause it to shrink back against the bottle in order to get a neat package; or if a wrapping material has been used that is normally elastic as thin vulcanized rubber with provisions for heat or pressure sealing it between the members 117, in any of these cases it will be seen that air would be trapped between the bottle and the wrapping material which would be objectionable for obvious reasons. The present invention overcomes such trapping of air by the provision of a small aperture through the fused or sealed edge portion of the wrapping material which will be understood by reference to Figs. 1, 2 and 3 wherein is disclosed a small groove 145 cut across the member 119 in such manner as to cause the wrapping material 124 to be drawn into said groove with the result that the entire portion of said material held on the members 117 will be fused or sealed together except over the grooves 145 whereby a small air escape passage is provided for the outward flow of air from between

the wrapping material and the bottle as the wrapping material shrinks back against the bottle to form snug fit there against. After this shrinkage has taken place this air escape passage may be sealed by pressing its edges together and heat sealing it or in any other manner found satisfactory. After the bottle has been entirely enclosed within the wrapping material 124 it is released from the wrapping mechanism as the crank shaft 106 returns to its lowest position thus reversing the motion of the mechanism's parts as will be readily understood by those familiar with mechanical motions. It will also be understood that the turn buckles 113 function to adjust the pressure between the members 117. Obviously stopping mechanism at the end of a cycle of the machine's motion may be provided and the hinge-like motion of the members 117 and 119 can be accomplished by various mechanical arrangements.

In describing the preferred form of the present invention I have referred to the sheet wrapping material as thermoplastic and have also referred to commercially available sheets by their trade names of "Pliofilm" "Koroseal" and "Kodapak," however, I do not intend my invention to be limited to the use of these or any other particular material. Obviously a thin sheet of stretchable wrapping material would work satisfactorily without the method step of softening. Also that thin wrapping material that would become softened and stretchable with a spray of water, alcohol or other substance, would not require the heat treatment referred to in some cases but would require its own special softening treatment according to the material being used. It is pointed out here, however, that one material found satisfactory for stretch-wrapping in all of the forms of the invention described in detail in connection with the apparatus shown herein is a thin sheet of rubber hydrohalide such as that disclosed in the Calvert Patent No. 1,989,632 to which reference is made for a disclosure of one suitable wrapping material for use in practicing this invention.

From the foregoing it will be evident that I have provided novel method steps and apparatus for covering various articles. The invention is susceptible of numerous modifications other than those specifically described and illustrated, and the right is herein reserved to make such changes as fall within the scope of the appended claims without departing from the spirit of the invention.

This application is a continuation in part of application Serial No. 193,214, filed February 28, 1938, and a substitute for application Serial No. 407,083, filed August 15, 1941, now abandoned.

I claim:

1. Packaging apparatus of the class described, comprising a supporting frame in which is mounted a crank shaft rotatably connected with arms which in turn are pivotally attached to toggle arms, said toggle arms being connected to said supporting frame through movable pivot pins and fixed pivot pins, said toggle arms being pivotally attached to sheet material channelled holding means support frames, said support frames being supported by a hinge pin in a similar manner to the leaves of a hinge, the channel of said channelled frame containing a vacuum sheet material holding members in the form of inserts whose top portions are formed with a shallow vacuum chamber whereby a substantial area of said vacuum chamber is exposed to a sheet of wrapping material when such sheet is in posi-

tion on said holding members, said channelled frames being shaped to conform to the shape of and to hold together over at least a part of an object being enclosed in said sheet wrapping material in a packaging operation.

2. A wrapping unit in the form of a clamp for holding a sheet of wrapping material and defining an opening to accommodate the object to be wrapped, said clamp having a substantially continuous gripping surface extending around the entire perimeter of the opening and comprising a pair of complementary sections arranged in hinged relation, said sections being movable to an open position for holding the sheet in substantially flat condition and being movable to a closed position for holding the sheet in folded condition with all its edge portions brought together in opposed parallel relation for extended contact in a single plane.

3. A wrapping unit in the form of a clamp for holding a sheet of heat-sealable and thermostretchable wrapping material and defining an opening to accommodate the object to be wrapped, said clamp having a substantially continuous gripping surface extending around the entire perimeter of the opening and comprising a pair of complementary sections arranged in hinged relation, said sections being movable to an open position for holding the sheet in substantially flat condition to permit the stretching of the sheet to partially enclose the object to be wrapped and being movable to a closed position after such stretching of the sheet to bring all its edge portions into heat-sealing engagement to complete the enclosure of the object.

4. A wrapping unit according to claim 2, wherein in the gripping surface of the clamp is formed with a vent to permit the escape of air from within the package resulting from the wrapping operations described.

5. A wrapping unit according to claim 2, wherein the gripping surface is created by vacuum means incorporated in the clamp.

6. A wrapping unit according to claim 2, wherein the complementary sections are made to approximate the shape of the object to be wrapped.

7. A wrapping unit in the form of a clamp for holding a sheet of wrapping material, said clamp being equipped with vacuum means for exerting a gripping action on the sheet and formed with a vent to permit the escape of air from within the package created by a complete enclosure of the object in said wrapping material.

8. A wrapping unit in the form of a clamp for holding a sheet of heat-sealable wrapping material, said clamp being formed with a vent to permit the escape of air from within the package created by a complete enclosure of the object in said heat-sealable material.

9. In the art of packaging, the method which consists in clamping a sheet of heat-sealable and thermostretchable wrapping material in substantially flat condition by a gripping action exerted thereon around its entire perimeter so as to hold fast to all the edge portions thereof, stretching the sheet while thus clamped to partially enclose the object to be wrapped, and then bringing the edge portions of the sheet together in opposed parallel relation for extended heat-sealing contact substantially throughout their entire extent to completely enclose the object.

10. A method as in claim 9, wherein the heat-sealing engagement of the edge portions of the sheet is complete except for a small vent left for bleeding the trapped air from within the package.

11. A method as in claim 9, wherein the heat-sealing engagement of the edge portions of the sheet is complete except for a small vent left for bleeding the trapped air from within the package, and thereafter closing up said vent by heat-sealing to render the package air-tight.

12. A wrapping unit in the form of a clamp for holding a sheet of wrapping material and defining an opening to accommodate the object to be wrapped, said clamp having a substantially continuous gripping surface extending around the entire perimeter of the opening and comprising collapsible and extensible sections, said sections when extended holding the sheet in substantially flat condition and when collapsed holding the sheet in folded condition with all its edge portions brought together in a common plane. 10

13. A wrapping unit in the form of a clamp for holding a sheet of heat-sealable and thermo-stretchable wrapping material and defining an opening to accommodate the object to be wrapped, said clamp having a substantially continuous gripping surface extending around the entire perimeter of the opening and comprising 20

5 collapsible and extensible sections, said sections when extended holding the sheet in substantially flat condition to permit the stretching of the sheet to partially enclose the object to be wrapped, and when collapsed after such stretching of the sheet holding all its edge portions in heat-sealing engagement to complete the enclosure of the object.
